UNITED STATES PATENT OFFICE.

AUGUSTUS MILLER, OF EAST ORANGE, NEW JERSEY.

DATING-STAMP LOCK.

1,352,300.

Specification of Letters Patent. Patented Sept. 7, 1920.

Application filed April 23, 1919. Serial No. 292,015.

To all whom it may concern:

Be it known that I, AUGUSTUS MILLER, a citizen of the United States, and a resident of East Orange, county of Essex, and State 5 of New Jersey, have invented a new and Improved Dating-Stamp Lock, of which the following is a full, clear, and exact description.

This invention relates to dating stamps 10 and more particularly to a locking means for use in connection with dating stamps.

An object of this invention is to provide means for use in connection with conventional and standard type dating stamps for locking the type in alined printing position.

It is also an object of this invention to provide a locking device which may be mounted upon the available space of the base plate of ordinary dating stamps, and 20 which will compressibly engage the several type carrying belts of the dating stamp for holding said belts in fixed relation for the purpose of preventing displacement of the printing type from their properly alined 25 service position.

With the above and other objects in view, this invention has relation to a certain combination and arrangement of parts to complete the locking means, used in connection 30 with a dating stamp, an example of which is described in the following specification, pointed out in the appended claims and illustrated in the accompanying drawings, wherein:—

Figure 1 shows a well known type of 35 dating stamp in front elevation, with the locking attachment comprising my invention, installed upon the base of said stamp.

Fig. 2 illustrates a vertical sectional view 40 of the dating stamp with the locking device shown in sectional view.

Fig. 3 is a perspective view of the locking attachment shown separate and apart from the dating stamp, with parts of the 45 stamp mechanism shown in dotted lines.

Referring further to the drawings, and more particularly to standard types of 50 dating stamps, the numeral 1 illustrates the frame member of said dating stamp, the lower frame portions being adapted to support and guide a base 2 in its upwardly swinging motion when it is moved into operation.

The base 2 of the stamp is provided with 55 an opening 3 through which the type carrying belts are adapted to expose the print-

ing face of type to be impressed against a surface, such as paper, to be printed. Drums or rollers 4 are rotatably mounted between upright spaced supporting brackets 60 5. The drums or rollers 4 are provided for carrying the belts which mount the type. The belts are designated by the numeral 6 upon which are fixed the printing type 7. The belts and type are made of flexible material and adapted to be passed around the drums selectively exposing any desired numbered type through the printing opening 3. The lower roller 4 is so disposed in the opening of the base as to bring the printing face of the type into the plane of the 70 surface to be printed.

Dating stamps of the character described are usually provided with one or more dated or numbered belts. Each belt and type set 75 is carried upon separate drums, and each drum is provided with a notched or serrated adjusting wheel 8. By proper selection of the numbered or dated belts and its adjusting wheel, the operator is able to expose and move into printing position any desired number for impressing the month, day and year upon paper. The printing mechanism is adapted to undergo an upwardly turning motion through an arc of 80 180 degrees for bringing the printing type into contacting position with the inking surface 9 usually provided in the upper portion of the stamp.

After a dating stamp has been used for 90 some time the drums and type carrying means correlated therewith become worn which causes looseness in fit. Therefore, an old dating stamp will not usually print straight line impressions, but will present 95 irregular and improperly alined printing type against the paper. The date carrying belts can be reset very conveniently through the use of the wheels 8 but they will not maintain their fixed position since the dat- 100 ing mechanism has lost its characteristic of firmness and friction.

It is, therefore, an object of my invention, as heretofore pointed out, to provide a simplified form of locking means to be mounted 105 upon the base of an ordinary dating stamp and used in connection therewith for the express purpose of locking one or many date carrying belts in fixed and immovable position relatively to the surface upon which a 110 printed impression is to be made.

With further reference to the drawings

and in particular to Fig. 3, there is shown a locking member or dog 15 comprising a body portion with an integral pressure head 16 and integral toe 17. This dog is provided 5 with pivot pintles 18 which may be integrally formed therewith. A carrier bracket 20 is provided with upturned ears 21 integrally formed at each end thereof. Small bores are drilled through the upturned ears 10 and pivotally support the pintles of the dog thus confining the dog in a movable relation upon the carrier bracket. The base 20 of the carrier is provided with suitable bores for the purpose of receiving screws used 15 for securing the locking device to the dating stamp. The dog is provided with a finger-piece 14 which may be integrally formed with the dog by punching it therefrom during the manufacturing operation. This 20 finger-piece can be engaged by the finger or thumb of the operator and swing the dog in outwardly disengaged position away from the belts. The dog is further provided with notches 13 to accommodate the adjusting 25 wheels 8. Thus the pressure head 16 will forcibly engage the belts by passing beyond the rim of the wheels 8 as illustrated.

An expanding pressure spring 22 is fixed to the base 20 of the carrier bracket and has 30 its upturned free end exerted in pressure contact against the toe of the dog thus keeping the pressure head 16 in forcible compressive contact with the date carrying belts 6. When it is desired to move the dating 35 belts into new position for exposing a different set of type numbers in the printing plane, the locking dog will be caught by the finger-piece 14 and pivoted outwardly about the point 18. This will permit a new arrangement of the dating device after which 40 the dog will again be swung into locking position and compressibly engage the belts as clearly shown in Fig. 2. In this figure is shown the actively engaged position of the 45 dog against the date belts, and in dotted lines is shown the outwardly disengaged position thereof.

The locking dog under the expanding pressure of the spring forcibly engages the 50 belt keeping it in frictionally engaged relation with the rollers, and so friction as to

securely hold the roller and belt in an immovable relation thus preventing displacement of the printing type alined at the printing plane. This form of locking dog 55 attachment is mounted upon the base 20 of the stamp by screws or other suitable means, and is accommodated upon the available space of the stamp base. The attachment undergoes the upwardly swinging motion 60 of the base and stamping means, and does not interfere in any way with the operation of the dating stamp.

The device may be built into a dating stamp as a unitary part, or may be installed 65 thereupon as a separate attachment depending upon the need and desire felt for improvements in this field of industry. The invention will fill a long-felt want in correcting errors and the usually poor operation 70 of the dating stamps in present day use.

Having thus described my invention, what I claim as new, and desire to secure by Letters Patent is:

75

1. A locking means for use on a dating stamp which has a printing mechanism mounted on a swingable base, comprising a bracket fixed upon the available space of the base, a dog pivoted on the bracket, a spring 80 disposed between the bracket and the dog for exerting pressure against said dog to confine it in engagement with the printing mechanism.

2. A locking dog for use in connection 85 with a dating stamp, where the dating stamp comprises a number of printing belts carried on spaced drums, said printing mechanism being carried on a swingingly mounted base, comprising in combination; a bracket 90 fixed to the base, a dog pivoted on the bracket and reaching upwardly, an engagement head made on the upper end of the dog to contact the printing belts below the tangential contact of the belts with the cylinder, a toe 95 made on the lower end of the dog, and a spring fixed on the base beneath the toe to exert pressure on the dog to forcibly thrust the engagement head against the printing belts.

AUGUSTUS MILLER.
